UNITED STATES PATENT OFFICE

2,474,642

SYSTEM FOR THE PREGINNING OF COTTON

Jeffrey J. Wallace, Amite, La., assignor to Gullett
Gin Company, a corporation of Louisiana

Application June 18, 1946, Serial No. 677,545

5 Claims. (Cl. 19—67)

1

This invention relates to a system for the pre-ginning treatment of cotton.

Now that mechanical harvesters are coming more and more into use, the problems of the ginner are multiplied. The mechanically gathered cotton is generally much dirtier than the hand picked product, containing more stems, leaves, dust, trash, boll fragments, etc., than hand picked cotton, and as a rule, requiring more extensive processing before passing to the gins. Thus, successive consignments of cotton brought to the ginning platform may require different degrees of processing. One batch may be hand picked and relatively clean, and require only a light processing. The next batch may be mechanically picked and heavily contaminated, requiring much more extensive cleaning. Then, too, there is a great difference in the degree of contamination in different batches of cotton, whether hand picked or mechanically harvested. The conventional ginning plant is equipped to provide only one uniform type of pre-ginning processing for all grades of said cotton, consequently, differences in the original contamination show up in the finished lint, frequently degrading the latter.

One of the objects of the present invention is to provide a system for the pre-ginning processing of cotton, which can be selectively adjusted to subject the cotton to more or less expensive processing, according to the degree of original contamination, whereby the finished lint will be uniformly clean, regardless of the original condition of the cotton.

Another object of the invention is to provide a system of the type described that will produce cleaner lint than can be achieved by the conventional system.

Other objects of the invention will appear as the following description of the invention develops.

The system of the present invention is adapted to employ conventional apparatus units, but connects them in novel combinations and sequences.

In the drawings which accompany and form a part of the following specification, and throughout the several figures of which the same reference characters have been employed to denote identical parts:

Figure 1 is a flow sheet illustrating the invention;

Figure 2 is a structural view in perspective, illustrating the system of the invention applied to a battery of four gins;

Figure 3 is a structural and elevational view,

partly in section, showing that part of the system associated with a single gin.

Referring now in detail to the several figures, and first advertizing to the flow-sheet, seed cotton from the wagon enters the multiple extractor 1, passes by way of conduit 2 into the dryer 3, from which it discharges by way of conduit 4 into the anterior or remote end of a distributor 5, which as shown in Figure 2, is an elongated tubular trough, extending longitudinally above the battery of gins 6, and as shown in Figure 3, houses the conveyor screws 7 which move the cotton forwardly, that is, towards the observer, in Figures 2 and 3.

At longitudinal intervals the distributor 5 is provided with outlets 11, from which the cotton is distributed by way of the individual conduits 8 to the hoppers 9, shown in Figures 2 and 3, and the hoppers discharge into the supermultiple extractors 10, which in turn discharge into the gins 6. The hoppers 9 and supermultiple extractors 10, like the conduits 8, are individual to the respective gins.

Thus the cross-section of each of the conduits 8 need be only of such size as to pass a small stream of cotton, equal to the capacity of a single gin. In the conventional system there is a single supermultiple extractor for the entire battery of gins, receiving a large stream of cotton from the distributor sufficient for all of the gins. The smaller stream can be much more thoroughly cleaned by the individual supermultiple extractors than the large stream can be cleaned by a single supermultiple extractor.

The traverse of the cotton from the distributor direct through the conduits 8 to the supermultiple extractor 10 may for convenience be designated as path A. There are two alternative cotton paths from the distributor to the supermultiple extractor, these being designated as B and C in the flow sheet, path B which is for cotton of intermediate grade as regards dirtiness, placing supplementary cleaning devices in series with and ahead of the supermultiple extractor, as will appear, while path C, which is for the most heavily contaminated cotton, places additional supplementary cleaning instrumentalities in line with and ahead of those in path B.

From each of the distributor outlets 11, a conduit 12 extends for conducting cotton to paths B or C. A valve 13 controls the cotton discharge from the outlet 11. This is shown as a swinging gate, in Figure 3. In the full line position it blocks the conduit 12, directing the cotton through the path A, which has already been de-

scribed. When in broken line position, it blocks conduit 8 and shunts the cotton into conduit 12.

The conduit 12 at its lower end divides into two branches 25 and 26, the former conducting the cotton through path B, and the latter by way of path C. A valve 27 at the mouth of conduit 12 controls the selective flow of cotton through one or the other of these branches.

Branch conduit 25 leads to the cleaning units 14 and 15, unit 14 being a vacuum condenser in which vacuum is maintained by a suction pipe 16, communicating with a fan chamber 17 containing a suction fan (not shown), the latter discharging into a trench 20 containing a trash conveyor 21.

The unit 15 is a multiple drum cleaner, also having a drying and conditioning function, since hot air is blown into it through conduits 22 and 23. The drum cleaner has an underlying dust and trash hopper 24, which discharge into the fan chamber 17, and eventually into the trench 20. The cotton is elevated in the drum cleaner and discharges from the upper end thereof into the hopper 9.

From the cleaning units 14 and 15, the cotton passes to the hopper 9, from which it is normally drawn into the supermultiple extractor 10, passing therefrom to the gin 6.

When the valve 27 is swung to a position blocking branch conduit 25 and opening branch conduit 26, the cotton is diverted so as to pass first through the multiple extractor 28 and cleaner 29, and then by way of conduit 30 to the condenser 14, and serially through the cleaning instrumentalities 14 and 15 to the hopper 9 and normally through the supermultiple extractor 10 to the gin 6.

It is to be understood that the entire cleaning system, beginning with the conduit 11 which leaves the distributor, and including the serially connected cleaning apparatus units which constitute the alternative paths A, B and C, are individual to the gin 6 and duplicated for each gin in the battery of gins, and it is emphasized that since only a small stream of cotton sufficient to supply a single gin is fed through the conduit 11 and through the cleaning units in any one of the selected paths, the cotton will be cleaned more thoroughly than it is possible to clean a stream of cotton large enough to be later distributed to a plurality of gins.

For one reason or another, as for instance to clean the roll box, it is necessary from time to time to temporarily stop one of the gins of the battery, necessitating cutting off the flow of cotton to that gin. The following arrangement permits this to be done without interrupting the operation of the cleaning system. Each of the hoppers 9 is connected to a common conveyor trough 31, having a screw conveyor 32, which leads back to a storage bin 33. A gate valve 34 controls the outlet from each hopper. When in the broken line position shown in Figure 3, it directs the discharge of cotton from the hopper to the supermultiple extractor 10 and gin 6. When it is in the full line position shown, it blocks the passage to the supermultiple extractor and opens the hopper to the conveyor 32, so that the cotton destined for the interrupted gin is then discharged into the bin 33. This may be cotton from conduit 8, which has only passed through the preliminary cleaning and conditioning apparatus 1 and 3, or it may be cotton which has been processed in the cleaning apparatus constituting paths B and C. When the stopped gin is again put into operation, the flow of cot-

ton thereto is resumed simply by turning the gate valve 34 again to its broken line position.

At any desired time the cotton in the bin may be returned to the cleaning system by way of a conduit 35, which divides into branches 36 and 37, the former leading to the preliminary multiple extractor 1, and the latter to the distributor. A gate valve 38 at the mouth of conduit 35 may be turned to direct the cotton into either of the branch conduits 36 and 37. Thus the cotton from the bin may be completely reprocessed, or alternatively, be made to by-pass the preliminary processing apparatus and go direct to the distributor 5, from which it may be selectively sent through any one of the paths A, B and C in the manner previously set forth.

The movement of cotton throughout the system from one apparatus unit to another is effected, aside from the mechanical conveyor herein disclosed, by a conventional air suction system which it has not been considered necessary to fully illustrate or describe.

It will be understood that the invention does not lie in the specific cleaning and conditioning instrumentalities per se, any or all of which may be old in the art, but it resides in their novel arrangement, and the manner in which they are connected, and in which the traverse of cotton therethrough is selectively controlled whereby it may be selectively subjected to various degrees of cleaning according to the condition of the seed cotton.

Referring to the flow sheet, the following apparatus therein designated may be exemplified by the apparatus disclosed in the following patents:

Multiple extractor 1, multiple extractor 28—Patent 1,953,545, Jeffrey J. Wallace, granted April 3, 1934.

40 Drier 3—Patent 1,707,929, Charles A. Bennett, granted April 2, 1929.

Cleaner 29—Patent 2,235,469, Jeffrey J. Wallace, granted March 18, 1941.

Condenser 14—Patent 1,081,111, T. S. Grimes, granted December 9, 1913.

Drum cleaner 15—Patent 1,369,716, Grover C. Stacey, granted February 22, 1921.

Supermultiple extractor 10—Patent 1,967,567, Jeffrey J. Wallace, granted July 22, 1934.

50 What I claim as my invention is:

1. A system for the pre-ginning processing of cotton comprising a battery of a plurality of gins, a distributor for distributing cotton to each of the 55 gins of said battery, an extractor and drier common to said gins anterior to said distributor discharging into said distributor, and a series of processing instrumentalities individual to each gin, between said distributor and gin through 60 which cotton passes to the gin, said series including an extractor adjacent said gin, an intermediate group including a vacuum condenser and drum cleaner, and a group at the head of said series including an extractor and cleaner, a conduit for each gin at spaced points in the length 65 of said distributor for supplying cotton to the gins, said conduit having branches communicating with said series respectively between said adjacent extractor and said intermediate group, between 70 said intermediate group and head group, and anterior to said head group, and selectively operable means for determining the flow of cotton into any one of said branches whereby it is passed to said gin through said adjacent extractor only, serially through said intermediate group and said

75

adjacent extractor, or serially through said head group, intermediate group, and adjacent extractor.

2. A system for the pre-ginning processing of cotton comprising a battery of a plurality of gins, a distributor for distributing cotton to each of the gins of said battery, an extractor and drier common to said gins anterior to said distributor discharging into said distributor, and a series of processing instrumentalities individual to said gins between said distributor and gin through which cotton travels to the gin, said series including an extractor adjacent said gin, an intermediate group including a vacuum condenser and drum cleaner, and a group at the head of said series including an extractor and cleaner, a conduit for each gin at spaced points in the length of said distributor, sized to pass a cotton stream equal to the capacity of a single gin, said conduit having branches communicating with said series respectively between said adjacent extractor and said intermediate group, between said intermediate group and head group, and anterior to said head group, and selectively operable means for determining the flow of cotton into any one of said branches whereby only enough cotton to feed one gin is passed to said gin through said adjacent extractor only, serially through said intermediate group and adjacent extractor, or serially through said head group, intermediate group and adjacent extractor.

3. A system for the pre-ginning processing of cotton comprising a battery of a plurality of gins, a distributor for distributing cotton to each of the gins of said battery, a preliminary extractor and drier common to said gins anterior to said distributor discharging into said distributor, and a series of processing instrumentalities individual to each gin between said distributor and gin through which cotton passes to the gin, said series including an extractor adjacent said gin, a hopper next anterior thereto discharging into said gin, an intermediate group including a vacuum condenser and drum cleaner, and a group at the head of said series including an extractor and cleaner, a conduit for each gin at spaced points in the length of said distributor for supplying cotton to the gins, said conduit having branches communicating with the said series respectively at said hopper, at a point between said head and intermediate groups, and at a point anterior to said head group, said intermediate group discharging into said hopper, selectively operable means for determining the flow of cotton into any one of said branches whereby it is passed to said gin by way of said hopper, alternatively through said adjacent extractor only, serially through said intermediate group and said adjacent extractor, or serially through said head group, intermediate group and adjacent extractor, a storage bin, a conveyor common to all said hoppers leading to said storage bin, a valve for each hopper operable to divert the cotton flow away from said gin into said conveyor, a discharge from said storage bin having branches connected to said extractor anterior to said distributor, and to said distributor, and means operable for directing the cotton flow from said bin to said extractor anterior to the distributor, or to the distributor.

erable to divert the cotton flow away from said gin into said conveyor.

4. System as claimed in claim 3, including a conduit from said bin with branches leading to said preliminary extractor and to said distributor, and a valve in said conduit operable to alternatively divert cotton flowing from said bin through said conduit, into either of said branches.

5. A system for the pre-ginning processing of cotton comprising a battery of a plurality of gins, a distributor for distributing cotton to each of the gins of said battery, an extractor and drier common to said gins anterior to said distributor discharging into said distributor, and a series of processing instrumentalities individual to each gin, between said distributor and gin through which cotton passes to the gin, said series including an extractor adjacent said gin and a hopper next anterior thereto discharging into said gin, an intermediate group, and a group at the head of said series, a conduit for each gin at spaced points in the length of said distributor for supplying cotton to the gins, said conduit having branches communicating with said series, respectively at said hopper, at a point between said head and intermediate group, and at a point anterior to said head group, said intermediate group discharging into said hopper, selectively operable means for determining the flow of cotton into any one of said branches whereby it is passed to said gin by way of said hopper alternatively through said adjacent extractor only, serially through said intermediate group and said adjacent extractor, or serially through said head group, intermediate group and adjacent extractor, a storage bin, a conveyor common to all said hoppers leading to said storage bin, a valve for each hopper operable to divert the cotton flow away from said gin into said conveyor, a discharge from said storage bin having branches connected to said extractor anterior to said distributor, and to said distributor, and means operable for directing the cotton flow from said bin to said extractor anterior to the distributor, or to the distributor.
